UNITED STATES PATENT OFFICE.

ROBERT J. BRATTON, OF GEORGETOWN, ILLINOIS.

BURIAL-VAULT.

No. 911,027.

Specification of Letters Patent.

Patented Feb. 2, 1909.

Application filed August 7, 1908. Serial No. 447,471.

To all whom it may concern:

Be it known that I, ROBERT J. BRATTON, a citizen of the United States, residing at Georgetown, in the county of Vermilion and 5 State of Illinois, have invented a new and useful Burial-Vault, of which the following is a specification.

This invention relates to artificial stone burial vaults and has for its object to provide 10 a cement burial vault which is strong and durable in construction and practically air and moisture proof.

A further object of the invention is to provide a burial vault including top and bottom 15 sections, a receptacle secured to the bottom section, and a cover housed within the top section and forming a closure for said receptacle.

A further object is to provide means for 20 permitting the escape of gas from the inner receptacle, and means for spacing the casket from the bottom of the inner receptacle so as to permit the ready withdrawal of the lowering straps.

25 A still further object of the invention is generally to improve this class of devices so as to increase their utility, durability and efficiency.

Further objects and advantages will appear 30 in the following description, it being understood that various changes in form, proportions and minor details of construction may be resorted to within the scope of the appended claims.

35 In the accompanying drawings forming a part of this specification: Figure 1 is a longitudinal sectional view of an artificial stone vault constructed in accordance with my invention. Fig. 2 is a transverse sectional 40 view taken on the line 2—2 of Fig. 1. Fig. 3 is an enlarged detail sectional view showing the construction of the valve. Fig. 4 is a perspective view of the reinforcing core of the top vault section detached. Fig. 5 is a 45 similar view of the reinforcing member of the lower vault section detached.

Similar numerals of reference indicate corresponding parts in all of the figures of the drawings.

50 The improved vault forming the subject matter of the present invention comprises an outer receptacle including top and bottom sections 5 and 6, said sections being molded or otherwise formed of cement, concrete or 55 other plastic material. The lower section 6 is provided with a vertically disposed mar-

ginal flange 7 and is reinforced and strengthened by the provision of a core member preferably stamped or otherwise formed of sheet metal and comprising intersecting longitudinal and transverse strips 8 and 9, said strips being bent to form angularly disposed fingers 10 adapted to be embedded in the concrete forming the flange 7 so as to assist in reinforcing and strengthening said flange. The upper vault section 5 is also preferably reinforced and strengthened by a core member similar in construction to the core member of the lower vault section and including intersecting longitudinal and transverse strips 11 and 12 terminating in anchoring fingers 13, there being threaded openings 14 formed in the longitudinal strip 11 for engagement with the threaded shanks of supporting eyes or loops 15. The loops 15 afford a means for 75 lowering the upper section into the grave and are adapted to be removed prior to filling the grave and the apertures formed by said loops or eyes filled with cement or concrete so as to prevent moisture from entering the 80 interior of the vault.

Secured to the outer bottom section 6 is an inner bottom section or receptacle 16, the latter being preferably formed of metal and spaced from the marginal flange 7 to produce a cement receiving groove 17. The inner receptacle 16 is provided with a top or closure 18 also preferably formed of metal and of the same height as the section 16, the side walls of the section 18 being arranged to overlap the side walls of the section 16 with their low edges embedded in the cement in the groove 17 and resting on the inner face of the bottom section 6, as best shown in Fig. 2 of the drawings. The lower 95 section 16 of the inner receptacle is rigidly secured to the bottom section of the outer receptacle by means of threaded bolts 19 which pass through transverse bars 20 for engagement with threaded openings 21 formed in the transverse arms of the reinforcing member of the adjacent lower vault section. The heads 22 of the bolts bear against the transverse bars 20 and not only serve to lock the latter in engagement with the bottom of the inner receptacle 16 but also serve to prevent wear on said receptacle when the bolts are adjusted.

Disposed within the inner receptacle 16 are channel irons 23 which form housings for 110 the bars 20 and bolts 19 and also serve to reinforce and strengthen the inner receptacle.

and prevent the side walls thereof from being forced inwardly when cement is introduced within the groove 17. The angle bars or housings 23 also serve to space the coffin or casket above the bottom of the inner receptacle 16 so as to permit the ready withdrawal of the lowering straps prior to positioning the closure 18 and top section 5 on the vault.

10 Extending transversely through the walls of the inner and outer receptacles at the cement receiving groove 17 is a pipe section or tube 24 having its inner end flared at 25 and rigidly secured to the receptacle 16, the outer end of the pipe or tube being offset to form a seat 26 for the reception of a ball valve 27. The valve 27 serves to permit the escape of the gas from the interior of the vault due to decomposition of the body and 20 is normally and yieldably supported to its seat by means of a coiled spring 28, one end of which bears against the valve, while the other end thereof bears against a bar 29 extending transversely across the mouth of the 25 pipe or tube, as shown. The side wall or inner top section 18 is formed with a recess 30 for the reception of the tube 24, whereby the section 18 may be positioned upon or removed from the section 16 without coming 30 in contact with said tube.

By forming the lower section 6 with a marginal flange, the vault may be used in a grave having several inches of water in the bottom thereof, the cement in the groove 17 serving 35 to prevent the entrance of water to the inner receptacle in case the water in the grave should rise above the height of the flange. In using the vault the section 6 is lowered to the bottom of the grave and the groove 17 filled 40 or partially filled with cement or other plastic material. The coffin or casket is then lowered within the inner receptacle 16 and allowed to rest on the angle bars or casings 23, after which the lowering straps are withdrawn and the cover section 18 of the inner receptacle placed in position on said inner receptacle with the lower longitudinal edge of the section 18 embedded in the cement. The outer top section 5 is then positioned 45 over the section 18 with its lower longitudinal edges embedded in the cement and resting on the inner face of the bottom section 6 the eyes or loops 15 being subsequently removed and the openings formed by the removal of said eyes closed with cement or concrete, as before stated.

Attention is here called to the fact that the outer receptacle forms a casing or housing for the inner receptacle so as to prevent corrod़ing of the metal, while said inner receptacle forms an air and moisture proof compartment for the reception of the coffin or casket. It will also be noted that the coffin is supported above the bottom of the inner receptacle, while the mouth of the vent tube 24

communicates with the interior of the inner receptacle beneath the bottom of the casket so as to permit the ready escape of gas from said inner receptacle.

The vaults may be made in different sizes and shapes with the outer sections constructed of glass, terra-cotta, cement or other suitable material, it being preferable, however, to construct the outer receptacle of concrete and the inner receptacle of copper or sheet iron.

Having thus described the invention what is claimed is:

1. A burial vault including top and bottom sections, a receptacle secured to the bottom section, and having a compartment for the reception of a casket and a cover housed within the top section and forming a closure for said receptacle.

2. A burial vault including outer telescopic top and bottom sections, and inner telescopic top and bottom sections housed within the outer top and bottom sections and forming a compartment for the reception of a casket.

3. A burial vault including an outer bottom section provided with a vertical flange, an inner bottom section secured to the outer bottom section and spaced from the flange to form a cement receiving groove, an outer top section having its lower longitudinal edge seated in the cement receiving groove, and an inner top section forming a closure for the inner bottom section and housed within the outer top section.

4. A burial vault including outer telescopic top and bottom sections having reinforcing members embedded therein, inner top and bottom sections housed by said outer sections, reinforcing bars resting on the bottom inner section, fastening devices piercing said bars and engaging the reinforcing core of the bottom outer section, and casings forming housings for the fastening devices and serving to support a coffin in elevated position above the bottom of the inner section.

5. A burial vault including an outer artificial stone bottom section, an outer artificial stone top section resting on said bottom section, and an inner metallic receptacle comprising telescopic top and bottom sections housed within said artificial stone sections and adapted to receive a casket.

6. A burial vault including outer artificial stone top and bottom sections, inner metallic telescopic sections housed within the outer sections and forming a compartment for the reception of a casket, fastening devices for securing the lower inner telescopic section to the bottom outer section, and transverse angle bars forming housings for the fastening devices and also serving to support the casket above the bottom of the compartment.

7. A burial vault including outer top and

bottom sections, one of which is provided with a marginal flange, inner telescopic sections spaced from the flange of the outer section to form a cement receiving groove, 5 fastening devices securing one of the inner sections to the adjacent outer section, angle bars forming housings for the fastening devices, and a vent tube communicating with the interior compartment between said angle bars.

10 8. A burial vault including outer telescopic artificial stone sections, one of which is provided with a marginal flange, reinforcing strips embedded in the material forming 15 said sections and formed of intersecting longitudinal and transverse arms terminating in angularly disposed fingers, the fingers of the lower section being embedded in the flange, an inner receptacle housed within the 20 sections of the outer receptacle and formed of telescopic sections, transverse bars resting

on the bottom of the inner receptacle, fastening devices extending through the bars and engaging perforations in the reinforcing strip of the adjacent outer vault section, housings disposed within the inner receptacle at said fastening devices and forming supports for a casket, a vent tube extending through the walls of the inner and outer receptacles and communicating 25 with the inner receptacle, and supporting loops carried by one or the outer sections and threaded in suitable openings in the reinforcing core of said section.

In testimony that I claim the foregoing as 30 my own, I have hereto affixed my signature in the presence of two witnesses.

ROBERT J. BRATTON.
